CASH-REGISTER.

1,046,353.

Specification of Letters Patent.

Patented Dec. 3, 1912.

Application filed August 7, 1912. Serial No. 713,741.

To all whom it may concern:-

Be it known that I, CHARLES WEAR, a citizen of the United States, residing at Malden, in the county of Middlesex and State of Massachusetts, have invented an Improvement in Cash-Registers, of which the following is a specification.

This invention relates to improvements in cash-registers, particularly applicable to apparatus described in Patent #1,005,280, dated October 10, 1911, to Morris & Jamieson and is designed to improve the construction of the supporting and feeding-means for the ink-ribbon, whereby the ink-ribbon is moved by any of the push-rods employed to feed forward the check-strips and record-strip, instead of by means operated by or in connection with the type-writing carriage, and also its direction of movement reversed. In the apparatus of said patent a wide record-strip and a plurality of narrow check-strips are employed, the latter being arranged above the former, and the ink-ribbon is reflexed to extend over the several check-strips, and also between the check-strips and the record-strip, and the ends of said ribbon are connected with or are arranged upon a pair of rolls which are located at one side of the row of strips, and said ribbon passes over a roll which is located at the other side of said row of strips, and push-rods, corresponding in number to the number of check-strips, are employed to feed forward the check-strip and the record-strip which is associated therewith. Also in said apparatus means are provided for moving the ink-ribbon intermittently by a movement of the type-writing carriage, to present fresh surfaces to be impressed by the types, which admit of its being disengaged from its actuator to admit of the type-writing carriage being returned without moving said ribbon, and said means is also arranged to be reversed to cause the ribbon to move in the opposite direction. Moving the ink-ribbon by the type-writing carriage is objectionable. In the present invention said ribbon is moved by means operated by any of the push-rods, intermittently but progressively, and is, therefore, independent of the type-writing carriage, and automatic means are provided for reversing the movement of the ribbon, so that after it has been

drawn from one spool and wound upon the other, its direction of movement may be reversed, in order that it may be drawn from the spool upon which it has been wound and wound upon the spool from which it was drawn. In carrying out this feature of my invention intermittently but progressively operating driving-mechanism is provided, adapted to be operated by any of the push-rods, and clutches are provided for connecting either ribbon-spool with said driving-mechanism and at the same time for disconnecting the other spool therefrom, and reversing-means is provided for the ribbon-spools adapted to be operated by the driving-mechanism and shifted by an axial movement of the spools and controlled by the ribbon on the spools, so that when the ribbon has been withdrawn from either spool, said spool is moved axially in one direction for connection with the driving-mechanism and the other spool is moved axially in the other direction for disconnection therefrom.

Figure 1 is a plan view of a cash-register having means embodying this invention for supporting and feeding forward the ink-ribbon. Fig. 2 is a longitudinal vertical section of the apparatus shown in Fig. 1. Fig. 3 is an enlarged front view of the ink-ribbon and actuating-means therefor. Fig. 4 is an end view of the ink-ribbon actuating-means. Fig. 5 is a detail of the shifting-lever for the spools and means to hold it in yielding frictional engagement therewith. Fig. 6 is a detail of the clutch-mechanism connecting the driving-mechanism for the ink-ribbon with the strip-feeding mechanism. Fig. 7 is a detail of the clutch-mechanism connecting the strip-feeding mechanism with its actuator.

The push-rods are represented at 65 as reciprocal and arranged horizontally and in parallel relation with each other. Said rods, when thrust inward, operate means to draw narrow strips of paper 53, herein termed check-strips, from rolls 66 and feed them forward, (see Fig. 2), and also operate means to rotate a roll 50, thereby to draw a wide strip of paper 46, herein termed a record-strip, from a roll 47, and wind it upon said roll 50. The record-strip 46 passes over a platen or roll 43; and the check-strips pass over rolls 58, and thence

between plates arranged concentrically about a portion of said platen or roll 43, so that the check-strips are associated with the record-strip in passing around the platen 5 or roll 43.

10 The push-rods 65 have rack-teeth 200, formed on them, for a short distance at their inner ends, and the rack toothed portions of the rods engage toothed-gears 63, which in turn engage pinions 61, (see Fig. 7), mounted loosely on the shaft bearing the rolls 58, and the hubs of said pinions have clutch-members 62, which are pressed by springs into engagement with fellow clutch-members 64 on the hubs of the rolls 58, so that said pinions may be moved rotarily in opposite directions to intermittently but progressively advance the rolls 58 and feed forward the check-strips.

20 Four check-strips are herein employed, which are arranged in a row, consequently four push-rods 65 are provided, each rod having means to feed forward its check-strip separately, as desired, and the record-strip which is employed is made wide enough to include all said check strips and also preferably to provide a portion at one side which extends beyond the end of the row of check-strips. An inking-ribbon 100 25 is arranged to move between the record-strip and check-strips and also above the check-strips, and the plates which are arranged about a portion of the platen have holes through them so that upon depression 30 of any one of a set of pivoted type-bars 78, by means of its pivoted actuating-member 85, a record will be printed upon the check-strip and also upon the record-strip.

35 The type-bars are borne by a carriage 40 which is movable transversely with respect to the machine to bring the type-bars into proper position to print upon any of the check-strips, and, as four check-strips are here shown, said carriage has four positions into which it may be brought for operation. When the ribbon is arranged for 45 operation by a rack-bar, or other means connected with the carriage, as represented in the aforesaid patent, it will be noted that 50 as the carriage is moved from one to another check-strip, said ribbon will be correspondingly and unnecessarily moved, hence the desirability of providing means for operating the ribbon which is independent of the 55 carriage.

60 The mechanism embodying this invention to support and to feed forward the ink-ribbon will now be described. 300 represents a pinion mounted loosely on a shaft 301, (see Figs. 4 and 6), and connected by a clutch 65 with said shaft, substantially in the manner shown in Fig. 7, whereby said shaft 301 is rotated intermittently but progressively by the pinion, and said pinion 300 is engaged by the toothed gear 63, (see Fig. 2), which

is engaged by the longitudinally reciprocating push-rod, so that the shaft 301 is operated by the push-rod. Said shaft 301 is arranged horizontally and in parallel relation with the front of the machine. On 70 said shaft 301, there are several pinions 300, one for each gear 63, and push-rod. Said shaft 301 serves as the driving-shaft for the driving-mechanism of the ink-ribbon, and, as here shown, said shaft has secured to it 75 a bevel-gear 303, which engages a bevel-gear 304, secured to a shaft 305, arranged horizontally and at right angles to the shaft 301, and said shaft 305 bears a bevel-gear 306, which engages a bevel-gear 307, secured 80 to a vertical shaft 308, bearing two bevel-gears 309 and 310. The gear 309, secured to a bevel-gear 312, (see Fig. 3), secured to a horizontal shaft 313, bearing a bevel-gear 314, which engages a bevel-gear 315, secured 85 to a horizontal shaft 316. The bevel-gear 310, engages the bevel-gear 320, secured to a horizontal shaft 321. Said bevel-gears 309 and 310 are disposed on the vertical shaft 308 in opposite ways so as to drive the shafts 90 316 and 321 in opposite directions. Two spools 325, 326, to which the ends of the reflexed ink-ribbon are attached are mounted respectively upon said shafts 316 and 321, and are freely rotatable and also movable 95 axially, and the hub of each spool has thereon a co-operative part of a clutch 327, 328, for engagement with fellow-members secured respectively to said shafts 316 and 321, so that said spools are adapted for engagement with and disengagement from their 100 shafts. Said spools are normally disposed with one of them in engagement with its shaft, and the other free from engagement with its shaft, so that one spool is positively 105 driven to draw the ink-ribbon from the other spool by winding said ribbon upon the positively driven spool, and, it will be noted, that each time any of the push-rods are pressed inward the driving-mechanism for 110 the ribbon-spools is operated intermittently but progressively, and the ribbon is correspondingly moved. When the ribbon has been withdrawn from one of the spools and wound upon the other it is necessary to reverse its direction of movement, and, herein, this result is accomplished automatically by 115 disengaging one of the spools from its shaft and engaging the other spool with its shaft.

120 As here shown, each shaft 316 and 321 has secured to it a worm 330, 331, and each spool carries a detent-arm 332, 333, pivotally supported on the spool, the outer ends of said detent-arms being arranged for engagement with said worms and the inner 125 ends of said arms being extended across the space between the heads of the spools. The pressure of the ribbon upon the inner ends of said arms acts to depress said ends, thereby to lift their outer ends free from engage- 130

ment with the worms, and springs are employed for moving their outer ends into engagement with the worms when pressure upon their inner ends is relieved, as for instance, upon withdrawal of the ink-ribbon from the spool. As represented in Fig. 4, the ink-ribbon has been withdrawn from the spool 326, and wound upon the spool 325, hence the detent-arm 333 is moved into engagement with the worm 331, and the detent-arm 332 is disengaged from its worm 330, and as the shaft bearing said worm 331 is rotated with the detent-arm in engagement with the worm, the spool bearing said arm is moved axially and its clutch-member 328 moved into engagement with its fellow-clutch-member, thus connecting said spool with its shaft.

A rocking-bar 340, pivoted at 341, at a point intermediate its length, is arranged at the one end of the two ribbon spools, the ends of said bar respectively engaging the hubs of said spools, and said bar is held by means of a spring 342, connected to its pivot, (see Fig. 5), in frictional engagement with said hubs, so as to retard rotary movement of the spools, thereby to prevent their too free rotation, although said bar is provided more particularly to serve as a means whereby each spool, when moved axially will in turn move the other spool axially. When the spool 326, (see Fig. 4), is moved axially, in a direction toward the left to cause its clutch-members to engage, said rocking-bar is moved on its pivot, thereby to move the spool 325 axially in the opposite direction, and cause its clutch-members to disengage, thereby disconnecting said spool 325 from its shaft, and when the spool 325 is moved axially in a direction toward the left said operation is reversed. Thus when either spool is moved axially in a direction toward the left, for engagement with its shaft, the other spool is moved axially in the opposite direction for disengagement from its shaft. Said rocking-bar is held in either position it may be caused to occupy, by means of an arm 345, secured thereto and having its free end made V-shaped and arranged for engagement with a V-shaped block 346, on the frame, the arm occupying a position at one or the other side of said block according to the position of the rocking-bar, it passing over said block when said bar is moved. My invention, however, is not limited to the particular form of driving-mechanism for the spools, or the means here shown for shifting the positions of the spools on their shafts, or controlling their operation.

I claim:

1. In a cash-register, the combination of a platen over which a plurality of check-strips arranged side by side are adapted to be fed, an ink-ribbon arranged over the sev-

eral check-strips, a carriage provided with typewriting mechanism, said carriage being movable to positions opposite the several check-strips, a plurality of push-rods, one for each check-strip, and means operated by each push-rod to feed forward a check-strip, and means also operated by each push-rod to move the ink-ribbon, substantially as described. 70

2. In a cash-register, the combination of a platen over which a record-strip and a plurality of check-strips arranged side by side are adapted to be fed, a reflexed ink-ribbon arranged over the check-strips and between the check-strips and the record-strip, a carriage provided with typewriting mechanism, said carriage being movable to positions opposite the several check-strips, a plurality of push-rods, one for each check-strip, and means operated by each push-rod to feed forward the record-strip and a check-strip, and means also operated by each push-rod to move the ink-ribbon, substantially as described. 80 85

3. In a cash-register, the combination of a platen over which a record-strip and a plurality of check-strips arranged side by side are adapted to be fed, a reflexed ink-ribbon arranged over the check-strips and between the check-strips and the record-strip, a carriage provided with typewriting mechanism, said carriage being movable to positions opposite the several check-strips, a plurality of push-rods, one for each check-strip, and means operated by each push-rod to feed forward the record-strip and a check-strip, and means also operated by each push-rod to move the ink-ribbon, substantially as described. 90 95

4. In a cash-register, the combination of a platen over which a plurality of check-strips arranged side by side are adapted to be fed, a carriage provided with typewriting mechanism, said carriage being movable to positions opposite the several check-strips, an ink-ribbon arranged over the several check-strips a pair of spools for the ends of the ribbon, driving-mechanism for said spools, a plurality of push-rods, one for each check-strip, means operated by each push-rod to feed forward a check-strip, and means also operated by each push-rod for operating the driving-mechanism for the ribbon-spools, substantially as described. 100 110 115

5. In a cash-register, the combination of a platen over which a plurality of check-strips arranged side by side are adapted to be fed, a carriage provided with typewriting mechanism, said carriage being movable to positions opposite the several check-strips, an ink-ribbon arranged over the several check-strips, a pair of spools for the ends of the ribbon, driving-mechanism for said 120 125 130

spools, means connecting said spools with the driving-mechanism involving reversing-means for the spools, a plurality of push-rods, one for each check-strip, and means 5 operated by each push-rod to feed forward a check-strip, and means also operated by each push-rod for operating the driving-mechanism for the ribbon-spools, substantially as described.

- 10 6. In a cash-register, the combination with a typewriting carriage bearing types, and operating-means for said types, a platen over which a strip of paper passes, supporting-means for the strip of paper, means to support an ink-ribbon over the strip of paper involving two axially movable spools, driving-mechanism for said spools, a push-rod, means operated by the push-rod to feed forward the strip of paper and also actuate said 15 driving-mechanism, and means controlled by the ribbon on the spools and operated by the driving-mechanism to move said spools axially into and out of engagement with the driving-mechanism, substantially as described.
- 20 7. In a cash-register, the combination with a typewriting carriage bearing types, and operating-means for said types, a platen over which a strip of paper passes, supporting-means for the strip of paper, means to support an ink-ribbon over the strip of paper involving two axially movable spools, driving-mechanism for said spools, a push-rod, means operated by the 25 push-rod to feed forward the strip of paper and also actuate said driving-mechanism, and means controlled by the ribbon on the spools and operated by the driving-mechanism to move said spools axially for engagement with the driving-mechanism, and means operated by either spool, when moved axially to engage the driving-mechanism, to move the other spool axially in the opposite direction to disconnect it from the driving-mechanism, substantially as described.

- 25 8. In a cash-register, the combination with a typewriting carriage bearing types, and operating-means for said types, a platen over which a strip of paper passes, supporting-means for the strip of paper, means to support an ink-ribbon over the strip of paper involving two axially movable spools, driving-mechanism for said spools involving two oppositely rotatable shafts which 30 support said spools, clutches to connect said spools with their shafts, worms on the shafts, levers borne by the spools for engagement with said worms, said levers being controlled by the ribbon on the spools, a push-rod, means operated by the 35 push-rod to feed forward the strip of paper and also actuate said driving-mechanism, and means controlled by the ribbon on the spools and operated by the driving-mechanism to move said spools axially for engagement with the driving-mechanism, and means operated by either spool, when moved axially to engage the driving-mechanism, to move the other spool axially in the opposite direction to disconnect it from the driving-mechanism, substantially as described.
- 40 9. In a cash-register, the combination with a typewriting carriage bearing types, and operating-means for said types, a platen over which a strip of paper passes, supporting-means for the strip of paper, means to support an ink-ribbon over the strip of paper involving two axially movable spools, driving-mechanism for said spools involving two oppositely rotatable shafts which 45 support said spools, clutches to connect said spools with their shafts, worms on the shafts, levers borne by the spools for engagement with said worms, said levers being controlled by the ribbon on the spools, a push-rod, means operated by the 50 push-rod to feed forward the strip of paper and also actuate said driving-mechanism, substantially as described.

- 55 10. In a cash-register, the combination with a typewriting carriage bearing types, and operating-means for said types, a platen over which a strip of paper passes, supporting-means for the strip of paper, means to support an ink-ribbon over the strip of paper involving two axially movable spools, driving-mechanism for said spools involving two oppositely rotatable shafts which 55 support said spools, clutches to connect said spools with their shafts, worms on the shafts, levers borne by the spools for engagement with said worms, said levers being controlled by the ribbon on the spools, a push-rod, means operated by the 60 push-rod to feed forward the strip of paper and also actuate said driving-mechanism, substantially as described.

- 65 11. In a cash-register, the combination with a typewriting carriage bearing types, and

operating-means for said types, a platen over which a strip of paper passes, supporting-means for the strip of paper, means to support an ink-ribbon over the strip of paper involving two axially movable spools, 70 driving-mechanism for said spools involving two oppositely rotatable shafts for said spools, clutches to connect said spools with their shafts, worms on the shafts, levers borne by the spools for engagement with 75 said worms, said levers being arranged for engagement with the ribbon on the spools, a cross-bar pivoted intermediate its length, the ends of which are arranged for engagement respectively with the spools, by which axial 80 movement of either spool in one direction is imparted to the other spool in the opposite direction, a push-rod, and means operated by said push-rod to feed forward the strip of paper and also actuate said driving-mechanism, substantially as described.

10. In a cash-register, the combination with a typewriting carriage bearing types, and operating-means for said types, a platen over which a strip of paper passes, supporting-means for the strip of paper, means to support an ink-ribbon over the strip of paper involving two axially movable spools, driving-mechanism for said spools involving two oppositely rotatable shafts for said 90 spools, clutches to connect said spools with their shafts, worms on the shafts, levers borne by the spools for engagement with said worms, said levers being arranged for engagement with the ribbon on the spools, a cross-bar pivoted intermediate its length, the ends of which are arranged for engagement respectively with the spools, by which axial 95 movement of either spool in one direction is imparted to the other spool in the opposite direction, a push-rod, and means operated by said push-rod to feed forward the strip of paper and also actuate said driving-mechanism, substantially as described.

11. In a cash-register, the combination with a reciprocating type-writing carriage bearing types and operating-means for said types, a platen over which a record-strip and a plurality of check-strips pass, the check-strips being arranged above the record-strip, means to support said strips, push-rods, and means operated by said push-rods to feed 115 forward said strips, a reflexed ink-ribbon arranged over the check-strips and between the check-strips and record-strips, a pair of spools for the ends of the ribbon, driving-mechanism for said spools involving two 120 oppositely rotatable shafts bearing said spools, on which said spools are movable axially, means to connect and disconnect said spools with their shafts upon axial movement thereof, and means operated by 125 130

any of the push-rods for actuating said driving-mechanism, substantially as described.

12. In a cash-register, the combination 5 with a reciprocating type-writing carriage bearing types and operating-means for said types, a platen over which a record-strip and a plurality of check-strips pass, the check-strips being arranged above the record-
10 strip, means to support said strips, push-rods and means operated by said push-rods to feed forward said strips, a reflexed ink-ribbon arranged over the check-strips and between the check-strips and record-strips,
15 a pair of spools for the ends of the ribbon, driving-mechanism for said spools involving two oppositely rotatable shafts upon which

said spools are axially movable, clutches for connecting said spools with said shafts, means operated by the driving-mechanism 20 and controlled by the ribbon on the spools for moving the spools axially in opposite directions to connect one spool with its shaft and disconnect the other spool from its shaft, and means operated by any of the 25 push-rods for actuating said driving-mechanism, substantially as described.

In testimony whereof, I have signed my name to this specification, in the presence of two subscribing witnesses.

CHARLES WEAR.
